UNITED STATES PATENT OFFICE

153,799

DESIGN FOR A BAG OR LIKE RECEPTACLE

Alex Hochner, New York, N. Y.

Application April 24, 1948, Serial No. 145,939

Term of patent 3½ years

(Cl. D87—3)

To all whom it may concern:

Be it known that I, Alex Hochner, a citizen of the United States of America and residing in the city, county, and State of New York, have invented a new, original, and ornamental Design for a Bag or Like Receptacle, of which the following is a specification, reference being made to the accompanying drawing, forming part thereof.

Fig. 1 is a perspective view of the bag in open condition, showing my new design;

Fig. 2 is a perspective view similar to that of Fig. 1, showing the bag in fully closed condition;

Fig. 3 is a bottom plan view of the bag of Fig. 1. The back of the bag is substantially plain.

The dominant features of my design reside in the portions shown in full lines.

I claim:

The ornamental design for a bag or like receptacle, substantially as shown and described.

ALEX HOCHNER.
